UNITED STATES PATENT OFFICE.

ALFRED H. HUMPHREY, OF NEW YORK, N. Y.

DESIGN FOR A GAS-STOVE.

51,557.

Specification for Design. Patented Dec. 11, 1917.

Application filed September 13, 1917. Serial No. 191,299. Term of patent 14 years.

To all whom it may concern:

Be it known that I, ALFRED H. HUMPHREY, a citizen of the United States, residing at 44 West Broadway, city of New York, county of New York, State of New York, have invented a new, original, and ornamental Design for a Gas-Stove, of which the following is a specification, reference being had to the accompanying drawing, forming a part thereof.

The figure is a front perspective of a gas stove showing my new design.

I claim:

The ornamental design for a gas stove as shown.

ALFRED H. HUMPHREY.

Witnesses:

EVERETT W. HOUSE,
H. E. HUMPHREY.
